UNITED STATES PATENT OFFICE

ALFRED C. CHRISTENSEN, OF CHICAGO, ILLINOIS, ASSIGNOR TO NATIONAL ENGINEERING COMPANY, OF CHICAGO, ILLINOIS, A CORPORATION OF ILLINOIS

DOOR-OPERATING MECHANISM FOR MIXING MACHINES

Application filed September 10, 1928. Serial No. 304,991.

This invention relates to door operating mechanism for mixing machines, and concerns itself with means for simultaneously operating a pair of doors by fluid pressure and maintaining the same in closed position.

The invention comprises a novel structure and combination of parts hereinafter described and more particularly pointed out and defined in the appended claims.

10 In the accompanying drawings which illustrate a preferred embodiment of this invention and in which similar reference numerals refer to similar features in the different views—

15 Figure 1 is a front elevational view of a mixing machine showing merely the mixing receptacle involving this invention.

Figure 2 is a view similar to Figure 1 with parts broken away.

20 Figure 3 is a side elevational view of the mixing receptacle.

Figure 4 is a fragmentary plan view taken on the line IV—IV of Figure 1 and looking upward in the direction of the arrows.

25 In the drawing there is shown a mixing receptacle 1 which is supported on suitable pedestals 2. The bottom of the receptacle is provided with a pair of discharge opening 3 which are adapted to be closed by discharge

30 doors 4. Adjacent the inner margin of each door opening 3 there is a rod 5 which is suitably journaled to the bottom of the receptacle and each door 4 has suitable castings or brackets 6 which are rigidly secured to the

35 rods 5 whereby the rotation of the rods 5 in the proper directions will cause the doors to be swung to their open or closed position.

It will be noted from an inspection of Figures 3 and 4 that the rods 5 extend beyond the periphery of the receptacle 1 and that arms 7 are rigidly secured upon the extended ends of the rods 5. The lower ends of the arms 7 are provided with shoulders 7^a. A link 8 is pivotally connected to each arm 7

45 just above the shoulder 7^a. It will be noted that each link 8 has a bifurcated end which straddles its arm 7 and the shoulders 7^a, which constitute stop members, extend beyond the bifurcations as shown in Figure 4

50 and thus limit the downward movement of

said links. The inner ends of the links 8 are pivotally connected to a bolt 9. The lower bifurcated end of a piston rod 10 is connected to the outer ends of the bolt 9 and confines the links 8 within the bifurcation thereof. 55 The upper end of the piston rod 10 extends into a fluid pressure cylinder 11 which is supported upon a suitable bracket 12 attached to the receptacle. A fluid supply pipe 13 provided with a three way valve 14 and a pair of branches 15 and 16 which respectively extend into the pressure cylinder 11 above and below the piston is provided for supplying the necessary fluid pressure to the cylinder. 60 The fluid may consist of air or the like. 65

When it is desired to open the discharge doors 4 the operator will manipulate the valve 14 for allowing fluid pressure to enter the lower part of the cylinder for elevating the piston. As the piston is elevated the 70 links 8 and arms 7 will be swung upwardly into the dotted line position shown in Figure 2. The shoulders or stop members 7^a engaging the links 8 as shown in dotted lines in Figure 2 thus limiting the upward pull on the piston rod and at the same time limiting the opening movements of the doors. 75

When it is desired to close the doors the operator will, of course, manipulate the three way cock so that fluid pressure will enter 80 above the piston and force the piston rod downwardly into the position shown in full lines for swinging the doors to their closed position. In this position the links are in alignment and hence upon dead center with the result that the doors will be held in their closed position. Further, if the fluid pressure is allowed to act upon the upper side of the piston the pressure thereof will also tend to maintain the doors in their closed 85 position. 90

From the foregoing it will be evident that a very simple door operating mechanism has been provided whereby the doors may be quickly opened and closed without any physical effort, and whereby a great deal of time and labor may be saved resulting in economy 95 of operation.

I am aware that many changes may be made and numerous details of construction 100

may be varied through a wide range without departing from the principles of this invention, and I therefore do not purpose limiting the patent granted hereon, otherwise than necessitated by the prior art.

5 I claim as my invention:

1. In a mixing machine embodying a receptacle having a pair of discharge openings, a pair of doors for closing said openings, a rotatable rod for supporting each door, an arm upon each rod, a link pivotally connected to each arm, a pivot pin connecting said links, an operating member connected to said pin, and means for maintaining said links upon dead center alignment for maintaining said doors in closed position, the said means comprising shoulders on the said arms positioned adjacent the ends to which the said links are pivoted to abut the said links and thereby limit their movement.

10 2. In a mixing machine embodying a receptacle having a pair of discharge openings, a rod journaled adjacent each of said openings, a door rigidly secured to said rod, an arm rigidly secured to said rod, a fluid pressure cylinder, a piston having a rod operating in said cylinder, control means for said fluid pressure, and links pivotally connecting said arms to said rod, each associated arm 15 and link having co-active terminal shoulders for engagement to maintain said links upon dead center alignment for maintaining said doors in closed position.

20 In testimony whereof I have hereunto subscribed my name at Chicago, Cook County, Illinois.

35 ALFRED C. CHRISTENSEN.
